UNITED STATES PATENT OFFICE.

LOUIS G. PETERS AND MORROW D. BROWN, OF DENVER, COLORADO.

DESIGN FOR A GERM-EXTERMINATOR FOR DRINKING-RECEPTACLES.

42,297.

Specification for Design.

Patented Mar. 12, 1912.

Application filed September 30, 1911. Serial No. 652,081. Term of patent 7 years.

To all whom it may concern:

Be it known that we, LOUIS G. PETERS and MORROW D. BROWN, citizens of the United States, residing in the city and county of Denver and State of Colorado, have invented a new, original, and ornamental Design for Germ-Exterminators for Drinking-Receptacles, of which the following is a specification, reference being had to the accompanying drawing, forming part thereof.

Figure 1, is a front elevation of a germ exterminator for drinking receptacles, showing our new design. Fig. 2, is a top plan view of a germ exterminator for drinking receptacles, showing our new design.

This device, embodying our new design, is primarily for dispensing disinfectant for disinfecting the mouth or rim of the drinking receptacle preparatory to using the said drinking receptacle, and is adapted to be stationed or supported in proximity to a drinking fountain or other source from which water or other liquid may be dispensed.

The design resides in certain features of construction which will now be described.

The device consists of a main receptacle whose front is circular and whose rear is flat. In the receptacle is arranged a housing and the circular front of the receptacle is provided with an arch-shaped opening in communication with the housing. An auxiliary receptacle is extended forwardly from the arch-shaped opening in the circular front of the main receptacle, while a disk is also extended forwardly from the opening in the circular front of the main receptacle and is supported above the auxiliary receptacle.

We claim:

The ornamental design for a germ exterminator for drinking receptacles, as shown and described.

LOUIS G. PETERS.
MORROW D. BROWN.
